UNITED STATES PATENT OFFICE.

JAMES N. CHILSON AND LOWTHER BROWN PUGH, OF FAIRMONT, WEST VIRGINIA.

COIN-CONTROLLED VENDING-MACHINE.

1,193,235.

Specification of Letters Patent. Patented Aug. 1, 1916.

Application filed August 17, 1915. Serial No. 45,952.

To all whom it may concern:

Be it known that we, JAMES N. CHILSON and LOWTHER BROWN PUGH, citizens of the United States, residing at Fairmont, in the 5 county of Marion and State of West Virginia, have invented certain new and useful Improvements in Coin-Controlled Vending-Machines; and we do hereby declare the following to be a full, clear, and exact description of the invention, such as will enable others skilled in the art to which it 10 pertains to make and use the same.

This invention relates to check controlled apparatus, and more especially to fraud 15 preventives; and the object of the same is to produce an apparatus of this character which cannot be actuated by the use of a washer, although the latter be of the same dimensions and weight as the coin. This 20 object is carried out by the mechanism hereinafter described and claimed, and as shown in the drawings wherein:

Figure 1 is a front elevation of this vending machine complete. Fig. 2 is a vertical 25 section of the check controlled apparatus, taken on the line 2—2 of Fig. 1 and slightly enlarged. Figs. 3 and 4 are plan views of the top plate and check carrier respectively; Fig. 5 is an enlarged perspective of a portion 30 of the under side of the carrier, and Fig. 6 is an enlarged perspective of a portion of the upper side of the bed plate. Fig. 7 is a sectional detail on the line 7—7 of Fig. 6. Fig. 8 is an enlarged perspective 35 detail of the device for holding the globe ring in place, and Fig. 9 a perspective detail of the means for preventing the movement of said ring. Figs. 10 and 11 are diagrams to be referred to hereinafter, showing 40 respectively the action of parts when a coin or a washer is inserted and the carrier moved. Fig. 12 is a vertical section through the drum and the mechanism for operating it, taken on line 12—12 of Fig. 3; Fig. 13 45 is a bottom plan of said drum; Fig. 14 a side elevation of its cap; and Fig. 15 a perspective detail of the lock for such drum.

Certain sections of this country are 50 flooded with metallic checks, slugs, or tokens (herein called "washers") which may have and often do have some little value but which under Federal requirements must be made with a hole through them; and clever manufacturers are making these

washers of the same diameter, thickness, and 55 weight as nickels (which we will herein refer to as "coins") with the object of permitting their use in coin controlled apparatus which are intended for nickels alone. There has therefore arisen a demand for a 60 fraud preventive mechanism whose principle of operation depends on the fact that the check is not perforated. This can be associated with other devices for prohibiting the insertion of too large a coin, preventing the 65 manipulation of the apparatus when too small a coin is inserted, etc. While it is possible that this device may be applied to check controlled apparatus of a variety of 70 types and for a variety of purposes, we have shown it herein as associated with a machine having a swinging or oscillating check carrier, the same serving also to carry an article from a stack within the hopper of the vendor to the outlet. It will be quite obvious, however, that the check controlled apparatus 75 might take other forms, and of course it is not necessary that it be associated with a vending mechanism of the precise character disclosed. The shapes, proportions, and 80 materials of parts are matters of no moment, and many features are briefly referred to herein because they are well-known in this art.

In Figs. 1 and 2 is shown a circular or 85 shell-like base 1 having a bottom 2 held in place by a lock 3 so that it may be removed to give access to the money chamber 4. Within this base is a chute 5 leading to the outlet 6 for the articles being vended, and 90 immediately above the outlet is the coin inlet slot 7. The top of the chamber 4 constitutes the bed plate 8, and may well be cast as a part of the shell of the base, and we prefer to form it with a peripheral bead 95 9 and an annular groove 10 inside the same.

The carrier 11 (see Fig. 4) stands next above the bed and has an upright peripheral rim 12 traveling in said groove 10 and a radial handle 13 which projects through a 100 slot 14 best seen in Fig. 1. This carrier has a skeleton form of body with spokes 15 and a hub 16, the latter resting on a hub or boss 18 rising from the center of the bed.

The top plate 21 (see Figs. 2 and 3) has 105 an annular rim 22 which is flanged as at 23 to engage within the bead 9 outside the rim 12 of the carrier, and this plate has a de-

pending hub 26 resting upon the hub 16 of the carrier. Its rim also has an upstanding bead 29 which may well be employed as seen in Figs. 8 and 9. That is to say, a ring 30 5 fits over this bead and over flange 31 at the lower end of a globe 32. The ring has a number of L-shaped feet 33 depending from it and adapted to pass through holes 34 in the plate 21, and thereafter if the ring is 10 turned slightly on the bead 29 the toes 35 of its feet engage under said plate and the ring and globe cannot be removed. To hold the ring against retrograde movement it is provided with an ear 36 adapted to come up 15 against an ear 37 projecting from the rim 22, and a padlock 38 may be passed through holes in these ears as seen in Fig. 9. It is to be understood that the top plate rests on the bed which forms a part of the base, 20 and that the only moving member thus far described is the carrier which is interposed between said top plate and bed.

Around the front side of the bed plate just inside the coin inlet 7, it is thickened 25 to produce on its upper side an arcuate band or rest 40 in whose upper face is formed an arcuate groove constituting a track 41. At one end of the band and groove is a hole through the plate 8 constituting the article 30 outlet 42, and at the other end of the track is a hole constituting the coin drop 43 through which the coin or check falls into the chamber 4. At about the center of the band and adjacent the track is a hole 44 35 through the plate, for dropping or ejecting spurious coins, undersized coins, and washers; and opposite this hole 44 and on the other side of the track from it the face of the band 40 is provided with an inclined seat 40 45 whose forward end merges into the upper face of the band but whose rearward end is shaped to form an upright wall 46 which stands oblique to a radius of the bed such as indicated by the dotted line in Fig. 6. 45

Coacting with and overlying the parts just described is the structure on the bottom of the carrier as seen in Fig. 5. While this carrier is of skeleton formation as already stated, around its front side it has a rather 50 wide band 50, and into the lower face of this band is cut a channel 55 which is deepest at its peripheral end next the coin inlet 7, while its inner end 54 merges into the plane of the lower face of the band 50. The rear- 55 ward edge of the channel is scalloped as at 58, but its forward edge is formed into an abrupt upright wall 56 which stands oblique to a radius of the carrier as indicated by the dotted line in Fig. 5; and depending from 60 the lower face of the band 50 adjacent the scallop is a lug 51 which travels in the groove or track 41 in the bed band 40. Through the carrier at a point in rear of the channel is an opening 52 which constitutes 65 a pocket for the articles being vended, as

described below. We may remark that as the carrier is shown inverted in Fig. 5 the parts to the right in that view may be said to be rearward parts, while the parts to the right in Fig. 6 are forward parts.

The upper side of the carrier (see Fig. 4) is formed with a rectangular wall 62 around the pocket 52, and just forward of this wall it has an arcuate rest 63 with a depressed or inclined rear end 64 and upright teeth 61 on its inner side for a purpose yet to appear. About diametrically opposite the rest the carrier has an upright arcuate wall 65 forming a channel 66 in which lies a coiled spring 67, one end being connected with a lug 68 70 at the forward end of the channel, and the other end with a lug 69 depending from the top plate 21 at about the point indicated in Fig. 3. The tension of this spring holds the carrier normally in such position that the shank of its handle 13 stands at the rear end of the slot 14, at which time the pocket 52 is directly over the article outlet 42, and therefore when pressure on the handle is released and the parts are returned by the 75 spring to their normal position, the article within the pocket drops through the outlet 42 and runs down the chute 5 to the main outlet 6 within reach of the customer.

The top plate 21 overlies the carrier and is 80 supported by its rim 22, screws or bolts 70 passing down through this plate and into the bed 8, and care being taken to so locate them with respect to the spokes 15 that the carrier may have its desired movements as will be 85 seen from Fig. 4. The top plate carries the hopper described below, and it is provided with an opening 72 directly underlying the hopper so that the lowermost of a stack of articles within the latter may pass through 90 this opening when the carrier is moved to bring the pocket 52 beneath it. At other times the rest 63 stands beneath said lowermost article and holds the stack within the hopper in a manner well understood in 95 apparatus of this character. Pivoted at 74 to the underside of the top 21 is a pawl 75 which is moved on its pivot by a spring 76 to throw its tip into engagement with the teeth 61 and the position of the pawl and 100 the length of the rest 63 and its rack of teeth are such that after the carrier has been moved so that the foremost tooth engages the tip of the pawl, the entire rack of teeth must be passed over the pawl before the latter 105 will disengage the last tooth and the carrier can be returned to its starting point. This detail of construction insures a full movement of the carrier from its normal position where the rest stands beneath the 110 hopper to its extreme opposite position where the pocket stands beneath the hopper. Therefore the lowermost article is sure to be dropped into the pocket, and when the carrier is returned to its normal position 115 120

125 130

this article slides down the chute 5 and is delivered to the operator without fail.

The fraud preventive mechanism is best illustrated in Fig. 7. The numeral 80 designates a latch whose beveled upper end 81 projects through a hole 82 in the band 40 at some distance in rear of the seat 45, while its lower end is pivoted at 83 to a lever 84 which in turn is pivoted at 85 near its front end 86 within the base and has its rear end normally raised by a spring 87. The numeral 90 designates a trip pin which has its upper end rounded at 91 and projecting through a hole 92 in the band 40 forward of the seat, while its lower end is pivoted at 93 to a rock lever 94 which in turn is pivoted at 95 within the base, and its rear end 96 underlies the front end 86 of the lever 84. Therefore anything which depresses the pin 90 rocks the lever 94, which in turn rocks the lever 84 and depresses the latch 80. Formed through the carrier just in rear of the channel 55 is an arcuate slot 88 into which the tip 81 of the latch normally projects, and this slot is of such length that a certain freedom of movement is permitted to the carrier for a purpose to be described below. Formed through the carrier yet in rear of the slot 88 is a hole 89 into which the tip 81 of the latch may project without lost movement, and this hole constitutes a catch.

The operation of the mechanism thus far described is as follows: With the parts standing in their normal position, a coin or im- 35 perforate check is inserted in the inlet 7 as seen at *a* in Fig. 10, and it passes onto the band 40 and under the top of the channel 55 as seen at *b*. The operator now grasps the handle 13 and turns the carrier so that its 40 slot 88 moves over the tip of the latch, and the lug 51 traveling in the track 41 moves the check forward as at *c* until it drops onto the seat 45. Continued movement of the carrier moves the check to the dotted position *d* in Fig. 10 when it slides over the rounded upper end 91 of pin 90, and if the check has no hole in it, this pin is depressed and the latch is tripped just in time to permit the rear end of the slot 88 to pass over 50 the tip of the latch. Continued turning of the carrier moves the check along over said tip 91 so that the check retains the pin 90 in depressed condition and this, through the levers, retains the latch 80 in depressed condition so that the catch 89 may move over 55 its tip 81 without engaging it; and the check is moved successively through the positions *e* and *f* to the position *g*, where it falls through the drop 43 into the chamber 4. At this time the shank of the handle 13 strikes the left end of the slot 14 as seen in Fig. 1 and checks the swing of the carrier just at a moment when its pocket 52 is under 60 the article chute which aligns with the opening 72 in the top plate. One article now

drops through said opening into the pocket and is supported on the band 40; and, when the carrier is restored to normal position either by moving the handle to the right or releasing it and permitting the spring 67 to contract, the pocket moves and slides the article along band 40 until the shank of the handle strikes the right end of the slot 14, at which time the pocket is directly over the outlet 42 and the article drops through the latter and runs down the chute 5 to the delivery outlet 6.

If a perforated check or washer is inserted as at *a'* in Fig. 11, it also will slip across the track 41 and under the channel 55 as in front of the lug 51, and then when the carrier is swung forward the lug traveling in the track will carry the washer with it. On reaching the position *c'* the edge of this washer engages the tip of the pin 90 and depresses it just at a time to depress the latch 80 and permit the rear end of the slot 88 to pass over its tip 81; but when the washer reaches the position *d'*, its hole permits the rise of the pin which, through the levers, permits the rise of the latch. The result is that said latch now engages the catch 89 and prevents further forward swing of the carrier; therefore the washer cannot pass through the positions *e* and *f* and be dropped as at *g* into the chamber 4. Now when the handle is released or turned back to normal position the oblique wall 56 (which it will be understood is in front of the washer) forces said washer backward to the position *e'*, and at this time its edge engages the rear oblique wall 46 of the seat 45 with the result that a shearing action between these walls takes place and the washer is moved radially inward to the position *g'* and drops through the hole 44 either into the chamber 4 or into the chute 5, in which latter case it is handed back to the would-be operator. If a thin check or coin such as a dime or a penny is inserted in the inlet 7, it is moved forward by the swing of the carrier to position *c'*, but the diameter of this coin being insufficient to permit it to reach the center of pin 91, it will not disengage latch 80. As the would-be operator releases the handle, the same action takes place as above described with the washer, the latch prevents a complete forward movement of the carrier, and the thin coin is ejected at *g'* through the hole 44. Obviously the size of the inlet 7 is such that too large a coin may not be inserted. Thus is provided a fraud preventive which is proof against the use of a washer that may have the same dimensions and weight as the coin which it is intended shall be employed with this machine, and is also proof against the successful use of under-sized or over-sized coins, checks, or washers. Obviously the tip 91 of the pin 90 may be made small enough to coat with

4
a smaller hole in the washer than that illustrated in Fig. 11.

The hopper referred to above may be a single and substantially upright chute down which the packages of gum or other material may slide, through the opening 72 in the top plate, and beneath which they will be handled as has already been explained; but we prefer to provide means for permitting the customer to select the article he prefers to purchase, so that if it be gum as herein described he can choose the flavor desired, and reference is now made to Sheet 3 of the drawings.

15 The numeral 100 designates a drum herein shown as having six sides and each of them provided with upright channels constituting hoppers 101, open at their front so that the edges of the packages of gum will be exposed and may be seen through the globe 32. The posts 102 will preferably therefore have flanges 103 along their sides, as seen in Fig. 13. The drum body may be hollow, closed by a top 104 and a bottom 105 both 20 pierced with central holes mounted on an upright shaft 106, which shaft extends down through the hubs of the several members of the check controlled apparatus and carries a bevel gear 107 at its lower end meshing 25 with another bevel gear 108. The latter is mounted on the inner end of a shaft 109 journaled in suitable bearings within the base 1, and on the front end of this shaft is a knob 110 standing alongside the main 30 outlet 6 as seen. It is obvious that the operator by turning this knob may bring any hopper 101 over the opening 72, and therefore may select the flavor of gum he prefers.

In order to align the hoppers successively 40 with said opening 72, we provide a hub 111 which is connected with the shaft 106 by any suitable means such as a key or pin 112, and a spur wheel 113 is made fast to the hub just above the top plate 21, its scallops 114 45 corresponding with the number of hoppers 101 in the drum. Pivoted at 115 to the top plate 21 is a lever 116 having a cam 117 whose face is rounded so that it may slip over the spurs of the wheel 113 and drop 50 into the scallops 114, and a spring 118 moves this lever to throw the cam into active position with yielding force. Thus when the operator turns the knob, he revolves the spur wheel which, with the drum, will come 55 to rest only when the cam engages one of the scallops and a certain hopper aligns with the opening 72.

In order to render the drum removable for cleaning or repair and to prevent lost 60 motion, we provide the upper end of the hub with pins 120, and the bottom 105 of the drum with a plate 121 around its center pierced with holes 122 adapted to engage 65 said pins; and above the top 104 a washer 124 is mounted on the shaft 106 and held re-

movably in place as by a screw 125. The cap 126 forming the apex of the drum may have a flange 127 which closes the upper ends of the hoppers, but this cap need not be fastened on the drum body and therefore it may 70 be lifted off to gain access to the screw 125. When the latter is withdrawn from the shaft 106 the entire drum can be lifted off the shaft. It is not necessary, however, to remove the drum when the hoppers are to be 75 replenished with packages of gum or other articles being vended. All that is necessary is to open the padlock 38 and remove it from the ears 36 and 37, turn the ring to disengage its toes 35 and lift its feet 33 out of 80 the holes 34, then lift off the globe 32 and cap 126, and supply the packages of gum to the upper ends of the hoppers 101. Doubtless this will be done by the druggist or other merchant in whose establishment the device 85 is set up, whereas from time to time a representative of the proprietor of the machine will come around, open the lock 3 and take the coins out of the chamber 4, and give the druggist the percentage thereof 90 agreed on. It is quite obvious that such coins could be nickels or other coins, and we do not wish to be limited in that respect; but the main purpose of this invention is carried out if the machine is such that it is 95 impossible to actuate its mechanism to deliver the goods by the use of perforated checks or washers which are so prevalent in certain parts of the country or by the use of 100 coins which are not of the size of those for which the machine is intended.

What we claim is:

1. In a check controlled apparatus, the combination with a circular hollow base containing a chamber whose top constitutes a fixed bed plate having an upstanding peripheral bead provided with a coin inlet and a slot in rear of the same, the bed plate having an ejector hole immediately forward of said inlet and a coin drop forward of the hole, a boss rising from the center of this plate, a top plate disposed above said bed plate and having a peripheral rim engaging said bead, and a hub depending from the center of this plate; of a movable carrier 101 pivotally mounted between said boss and hub and having a peripheral rim provided with a notch, a handle on the carrier movable within said slot, the carrier having a channel in its lower face communicating with its notch, a depending lug at the rear side of said channel for advancing a check as the carrier is swung forward, means for preventing its full forward movement when a washer is inserted, and means for ejecting said washer on the return movement of the carrier.

2. In a check controlled apparatus, the combination with a circular hollow base containing a chamber whose top constitutes

- a fixed bed plate having an upstanding peripheral bead provided with a coin inlet and a slot in rear of the same, the bed plate having a groove inside said bead and an 5 ejector hole immediately forward of said inlet and a coin drop forward of the hole, a top plate disposed above said bed plate and having a peripheral rim with a flange engaging said bead, and means for rigidly connecting said plates; of a movable carrier pivotally mounted between said plates and having a peripheral rim traveling in said groove and provided with a notch, a handle movable within said slot and secured to the carrier at 10 15 a point to strike the rear end of the slot when said notch registers with the coin inlet, the carrier having a channel in its lower face communicating with its notch, a depending lug at the rear side of said channel 20 for advancing a check as the carrier is swung forward, means for preventing a full forward movement of the carrier when a washer is inserted, and means for ejecting said washer on the return movement of the 25 carrier.
3. In a check controlled apparatus, the combination with a hollow base whose top constitutes a bed plate having a curved band around its front side provided with an ejector hole, the shell of the base having a coin inlet just in rear of said hole and the band having an arcuate groove constituting a track, and a top plate overlying said bed plate; of a movable carrier pivotally mounted 30 between the plates and having a channel adapted to aline with said inlet, a depending lug on the carrier at the rear side of said channel movable in said track for advancing a check as the carrier is swung, means 35 for preventing its full forward movement when a washer is inserted, and means for dropping said washer through the ejector hole on the return movement of the carrier.
4. In a check controlled apparatus, the 40 combination with a circular hollow base containing a chamber whose top constitutes a fixed bed plate having an upstanding peripheral bead provided with a coin inlet at the front of the base, the bed having a thickened band inside said inlet and provided in its upper face with an arcuate groove constituting a track, and the band having an ejector hole just forward of said inlet and a coin drop forward of the hole; of 45 a swinging carrier pivotally mounted over the plate and having a channel in its lower face adapted to aline with said inlet when the carrier stands at normal position, a depending lug at the rear side of said channel moving in said track for advancing a check as the carrier is swung, means for preventing its full forward movement when a washer is inserted, and upright walls oblique to radial lines and at angles to each 50 other, one at the rear side of said hole and the other at the forward side of said channel for forcing the washer into said ejector hole on the return movement of the carrier.
5. In a check controlled apparatus, the combination with a circular hollow base 70 whose top constitutes a fixed bed plate having an upstanding peripheral bead provided with a coin inlet, the bed having a band inside said inlet provided in its upper face with a depressed seat forward of the inlet and having an upright wall at its rear side oblique to a radius of the bed plate, said band having an ejector hole opposite the seat and a coin drop forward of the hole; of a carrier pivotally mounted 75 over the plate and having a channel in its lower face adapted to aline with the inlet when said carrier stands at normal position, the front side of said channel having an upright wall oblique to the radius of the carrier 80 and at an angle to said other wall, means at the rear side of said channel for advancing a check as the carrier is swung, means for swinging the carrier, and means for preventing its full forward movement 85 when a washer is inserted.
6. In a check controlled apparatus, the combination with a fixed bed plate having along its front edge a bead provided with a coin inlet, and a thickened band inside said 90 bead having a groove parallel with the bead and constituting a track, an ejector hole inside the track just forward of the inlet and a coin drop forward of the hole, the band also having between its bead and track and 95 opposite said hole a seat in its upper face whose front wall merges into said face and whose rear wall is upright and stands oblique to the length of the track; of a carrier movable over said band and having in 100 its lower face a channel whose outer end is adapted to aline with said inlet and whose inner end merges into said face, the front wall of said channel being upright and oblique to the length of the track and at an 105 angle to said other wall whereby said walls are adapted to coact with a shearing action on a washer resting on said seat, a lug depending from the carrier at the rear side of said channel and moving in the track for 110 advancing a check as the carrier is moved, means for moving the carrier, and means for preventing its full forward movement 115 when a washer is inserted.
7. In a check controlled apparatus, the 120 combination with a bed plate having a band leading from the coin inlet to the coin drop and provided with a seat within its length and an ejector hole opposite said seat, a carrier overlying said band and provided in its 125 lower face with a channel, the front wall of the channel and rear wall of the seat standing at angles to each other for forcing a washer through said ejector hole on the rearward movement of the carrier, and 130

means for moving the carrier; of a latch projecting through the band in rear of said inlet, yielding means for holding it normally elevated, a catch in the carrier at a point to engage said latch and prevent the full forward movement of the carrier, a push pin projecting through said band forward of the seat at a point to enter the hole in a washer, and connections between said pin and latch for depressing the latter as the former is depressed by a check.

8. In a check controlled apparatus, the combination with a bed plate having a band leading from the coin inlet to the coin drop and provided with a seat within its length and an ejector hole opposite said seat, a carrier overlying said band and provided in its lower face with a channel, the front wall of the channel and rear wall of the seat standing at angles to each other for forcing a washer through said ejector hole on the rearward movement of the carrier, and means for moving the carrier; of a latch projecting through the band in rear of said inlet, yielding means for holding it normally elevated, a catch in the carrier at a point to engage said latch and prevent the full forward movement of the carrier, a push pin projecting through said band forward of the seat at a point to enter the hole in a washer, a pivoted lever having one arm connected with said pin, a second pivoted lever having one arm connected with said latch, the other arms of said levers engaging each other so that depression of the pin causes depression of the latch, and a spring normally raising the latch to project its tip into said slot or hole, for the purpose set forth.

9. In a check controlled apparatus, the combination with a band extending from the coin inlet to the coin drop and provided with a seat within its length and an ejector hole opposite said seat, and a carrier overlying and movable along said band and provided in its lower face with a channel whose outer end is deep and adapted to pass said inlet and whose inner end is shallow, the front wall of the channel and rear wall of the seat standing at angles to each other for forcing a washer or small coin through

said ejector hole on the rearward movement of the carrier; of a latch having a beveled upper end projecting through the band in rear of said inlet, the carrier having a slot and forward of it a hole, both adapted to receive said beveled end, a push pin having a rounded upper end projecting through said band forward of the seat at a point to enter the hole in a washer, a pivoted lever having one arm connected with said pin, a second pivoted lever having one arm connected with said latch, the other arms of said levers engaging each other so that depression of the pin causes depression of the latch, and a spring normally raising the latch to project its tip into said slot or hole, for the purpose set forth.

10. In a machine of the class described, the combination with a hollow base containing a coin chamber whose top constitutes a fixed bed plate having a peripheral bead provided with a check inlet, the bed plate having an ejector hole forward of said inlet, a coin drop forward of the hole, and an article outlet rearward of the inlet, said base having a main outlet and a chute connecting it with said article outlet, and a top plate above the bed plate and resting on its bead and provided with an article opening out of registry with said article outlet; of a carrier movable between said plates and having a check channel alining with said inlet when the carrier stands at normal position, an open-ended pocket through the carrier alining with the article outlet at this time and adapted to aline with said opening in the top plate when the carrier is moved completely forward to drop a coin, means for preventing its full forward movement when a washer is inserted, means for ejecting such washer through said hole on a return of the carrier to its normal position, and an article hopper communicating with said opening in the top plate.

In testimony whereof we affix our signatures.

JAMES N. CHILSON.
LOWTHER BROWN PUGH.
